METHOD OF DEAERATION

John R. McDermet, Jeannette, Pa., assignor to
 Elliott Company, Jeannette, Pa., a corporation
 of Pennsylvania

Application January 28, 1932, Serial No. 589,368

2 Claims. (Cl. 183—2.5)

The present invention relates broadly to the art of deaeration, and more particularly to an improved method effective for the removal of air from water for the purpose of rendering available a continuous supply of deaerated water such as to satisfy the demands for example of a modern power plant or the like.

In the deaeration process, there are certain conditions which must be initially obtained and thereafter continuously maintained in order to insure the production of deaerated water within the commercially accepted sense. In accordance with certain known processes, it is customary to provide distinct stages of treatment through which the water passes successively during the deaerating process. The present invention relates more specifically to a multiple treatment zone apparatus and method of this general character.

In such apparatus, the water is usually brought into contact with heating steam in one of the zones which, by reason of its primary provision for heating purposes may be referred to as the heating stage. In this stage the water is raised to a temperature substantially as high as it is possible to raise it in the presence of air in the steam originally supplied for heating purposes plus the air released from the water during the heating operation, it being understood that the solubility of air in water is a function of the temperature and that the solubility decreases as the temperature increases. It is well recognized that this temperature differential between the full steam temperature of the supplied steam, and the water undergoing treatment, is such that there is a considerable air content left in the water. This air content is subsequently removed by subjecting the water to treatment in a second stage provided primarily for the purpose of effecting complete or substantially complete air elimination, and therefore commonly referred to as a deaerating or pressure stage.

The term "pressure stage" is significant in that in this stage the partial air pressure in the steam atmosphere is maintained so low that the air in the water passes out of the water in an attempt to establish a pressure equilibrium between the air content of the water and the air content of the ambient steam atmosphere. This pressure equality is in accordance with the law of Henry to the effect that gases, including air and its constituents, dissolve in water in proportion to their partial pressures at the surface of the water or in contact therewith.

In the two stage or two zone treatment herefore provided, it has been customary to provide

a thoroughfare type of steam heater constituting the pressure stage, and an induction type of heater constituting the heating stage, the heating steam passing first through the thoroughfare heater and thence into the induction heater, with the water passing in the reverse direction, i. e., first through the heating stage and thence into and through the deaerating stage. In this manner, water previously heated in the heating stage is subjected to the substantially pure steam atmosphere initially admitted to the pressure stage.

It is, however, open to the objection that all of the air from the pressure stage as well as the air released in the heating stage, are in more or less intimate contact with the water in the heating stage. In this stage the water being admitted contacts with this air-rich atmosphere in such manner that reabsorption of a considerable portion of the air is made possible. While this air is again released during the heating operation, it becomes apparent that the operation of the apparatus is inherently such as to require a re-handling of a considerable portion of the air content.

It is one of the objects of the present invention to provide a two stage or two zone type of water treatment wherein the water and steam instead of flowing counter one to the other, flow generally in the same direction in such manner that air once released from the water undergoing treatment is at no time permitted to contact with water at a temperature or under conditions such that reabsorption of the air is permitted.

In accordance with the present invention the water is subjected to successive treatments in different stages or zones. Each such zone provides a series of steam strata through which the water passes progressively, thus insuring a progressive increase in water temperature as the water passes from stratum to stratum in either stage. In order, however, to obtain the most beneficial results, it is desirable that the various strata be subjected to a steam withdrawal action, at least in the pressure stage, of such character that the stratum having the least temperature rise is subjected to the most effective withdrawal.

By way of general introduction, it may be assumed that in an apparatus of the tray type, the water is to pass successively over each of the desired number of trays. These trays will obviously define horizontally superimposed zones or strata through which the water progressively passes in going from one tray to the other. As

each of the strata is supplied with heating steam, the temperature rise in the first stratum will be greater since in this zone the coldest water comes into contact with the steam. Thereafter, the temperature rise will be a more gradual one, which may be considered as generally comparable to the time element together with the rate of air removal. Thus, in the last stratum of treatment the temperature rise will be of a minimum amount and, except for affording a possibility of pressure equilibrium of the character referred to, almost negligible.

Since, however, pressure equilibrium involves by its very nature the release of air from the water, and therefore air contamination of the steam atmosphere, it is essential that the steam atmosphere be continuously renewed. Since the temperature rise, as before stated, is almost negligible in the last stratum of treatment, the tendency toward any induced flow of steam into such stratum is likewise almost negligible. Under normal conditions of operation, there is a possibility of air stagnation in each stratum. It is one of the objects of the present invention to provide a method and apparatus characterized by the possibility of effecting continuous renewal of the steam atmosphere in such stratum by insuring a continuous passage of steam thereinto and its continuous removal therefrom.

Since, as before pointed out, the temperature rise in the successive strata is a decreasing one, the steam flow induced in such strata is likewise a decreasing one. It is further one of the objects of the invention to provide a method and apparatus characterized by the possibility of modifying the normal steam flow into such strata and establishing and continuously maintaining conditions such that the tendency toward steam flow into the various strata is progressively increased in the direction of water flow.

In accordance with the present invention, such a result may be accomplished by making provision for a more effective venting of the strata progressively in the direction of water flow whereby the last stratum is characterized by a greater potential venting capacity than the stratum preceding it, the capacity preferably decreasing gradually in a direction counter to the water flow, although any provision or disposition of parts whereby the desired preferential steam flow condition is obtained, responds to the present invention.

It is of course possible to utilize ejectors for accomplishing steam movement through an apparatus, or to supply steam under appreciable pressure and vent it in large quantities directly to the atmosphere. Both of these methods, however, are open to the objection that the heat of the steam thus withdrawn is lost. In accordance with the present invention, I preferably utilize a withdrawing or steam flow inducing means of such nature that it is possible to continuously recover the heat of withdrawn vapors and gases and impart the same to an appreciable extent to the water to be deaerated.

For this purpose I preferably utilize a two surface type vent condenser, such a piece of equipment being characterized by ability to withdraw vapors and gases and induce the desired flow conditions, and by the ability to transfer a large portion of the heat of the withdrawn mixture to the condensing medium. From purely commercial considerations, therefore, I preferably utilize such a vent condenser as the flow inducing means, passing therethrough the water to be deaerated as the condensing medium.

The accompanying figure of the drawing, which is largely diagrammatic, illustrates one form of apparatus by means of which the present invention may be practiced. In accordance with this diagrammatic showing there is provided a suitable casing 2 having a water inlet 3 leading into its upper portion. Disposed within the water inlet is a float operated valve 4 operatively connected to a float 5 disposed in the water storage space 6 in the bottom portion of the apparatus and therefore having its position determined entirely by the water level therein. Leading from the water storage space is an outlet 7 for the purpose of conveying deaerated water to the point of ultimate use. The position of the float is thus responsive to demands on the apparatus and the supply of water is correspondingly automatically controlled in accordance with the load.

Leading into one side of the apparatus adjacent the upper portion thereof is a steam inlet 8 communicating with a heating zone H. Within this zone is a series of conventional trays 9 such as customarily provided in water heaters of the open type. The admitted steam passes between the trays as indicated by the arrows 10 in the form of superimposed strata, leaving the same and passing downwardly as indicated generally by the arrows 11.

It is a desirability of the present invention that the heating zone H be characterized by its ability to accomplish the desired heating of the supplied water at an extremely rapid rate under favorable conditions of maximum temperature gradient, high steam velocities and the like. Its value resides substantially completely in its space or weight efficiency and its commercial inexpensiveness. In this heating compartment the water admitted to the apparatus is subjected in broken up condition to the action of the admitted steam in such manner that the temperature of the water is rapidly raised, thus effecting air elimination. This eliminated air together with the steam not condensed in the heating duty, pass into the pressure zone P in the manner before referred to. Within this zone there are placed in superimposed relationship trays 12 which again divide the steam flow into a plurality of superimposed strata, the strata leaving the trays as indicated by the arrows 14 and flowing downwardly as a solid stream through a space 15 between the water and the combined bottom tray 12 and partition 16.

By reference to the drawing it will be noted that the outlet spaces 17 from the successive trays progressively increase in size in a direction downwardly of the tray stack or in the direction of water flow, the outlet opening 17 for the bottom tray being of maximum size and therefore permitting the most free steam flow therefrom.

It will be realized that with an apparatus of the character referred to providing a steam and water flow in the same direction, the deaeration accomplished in the pressure zone P must be accomplished by the use of steam which has previously been appreciably contaminated by the air released in the heating zone H. From a theoretical standpoint, this is objectionable in that the air content of the steam, and therefore the partial pressure of the air, is greater in the pressure zone than in the admitted steam. From a practical standpoint, however, the objectionable increase in air tension may be effectively counteracted by supplying a greater heat quantity in the form of excessive steam, and by providing a slightly larger tray area than ordinarily considered necessary. This excess heat quantity

must in turn be removed from the apparatus and the heat thereof conserved.

For this purpose, I connect the space 15 to the vapor inlet 18 of a vent condenser 19 and 5 cause the air-steam mixture to pass in intimate contact with the condenser tubes 20 through which the water flows from an inlet 21 to an outlet 22, the outlet 22 being suitably connected to the inlet 3 as indicated in the drawing. The 10 condenser is provided with the usual vent 23 either permitting the uncondensable content of the mixture to discharge directly to the atmosphere, or provided with an ejector or air pump as operating conditions dictate.

15 With an apparatus of the character referred to, the vent condenser is made considerably larger than vent condensers as customarily designed for water handling apparatus of the same size, whereby excessive venting and therefore excessive steam flow is constantly insured. Inasmuch as the heat of the vented mixture is imparted to the water to be deaerated, the operating cost of the apparatus is not so increased as to detract appreciably from its commercial use.

20 The vent condenser is thus initially proportioned to maintain enough condensing capacity to provide a deaerating atmosphere in the lower compartment. The necessary size of the vent condenser is calculated upon the basis of the 25 maximum load, keeping in mind the established temperature conditions. In actual practice, these conditions remain constant but the load as measured by the quantity of water treated, varies.

It is to be noted that the quantity of water 30 passing through the vent condenser as cooling fluid subsequently reappears with the slight addition of the condensed heating steam, in the deaerating compartment, as the quantity of water being deaerated. The circulation of the 35 vent condenser for cooling purposes, therefore, is continuously in exact proportion to the quantity of water being treated, except for the slight condensate resulting from the heating steam. This 40 ratio of steam removed and condensed to the total quantity of water being handled thus remains constant, as will be obvious from a 45 consideration of the fact that the vent condenser cooling water circuit is in series with the deaerating circuit or, in other words, the water to be deaerated passes through the vent condenser to condense any steam remaining uncondensed 50 therein before passing to the heating and deaerating chambers.

The direction of the steam and water flow is 55 such that the released air is concentrated downwardly through the apparatus toward the water storage space. The water in this space has been heated to the highest temperature possible by the apparatus, and therefore represents a region 60 where the solubility of air in the water is at a minimum. By sweeping the venting steam across the water surface, any accumulated air is continuously removed, the point of air removal being from a region wherein the solubility of air in the 65 water is at a minimum and therefore overcoming the objections to forms of apparatus wherein the air is permitted to pass upwardly in the opposite direction as necessitated by a counter current steam flow, and thereby into contact with the 70 water where air solubility is at a maximum.

Knowing the initial air content of the water to be deaerated, and knowing the extent to which air removal is to be effected, it is possible to determine what the partial air pressure of the 75 remaining air in the water will be and to design the

apparatus so as to insure such an air-steam ratio in the pressure zone P that the partial air pressure due to the air in the air-steam mixture in this zone will be below the partial pressure of air in the water to be delivered from the apparatus. This desired air-steam ratio is continuously maintained by excessive venting, the vent condenser being designed to handle the necessary steam quantity to accomplish this object.

In abstracting heat from the vapor mixture, the vapors are necessarily condensed in the condenser, thereby decreasing the volume and tending to create a vacuum, this tendency being effective through the connection 18 for withdrawing further vapors from the apparatus into the condenser. The condenser thus constitutes a true withdrawal means, the effectiveness of which on the respective strata is determined by the size of the respective openings 17. By reason of the gradual increase in size of these openings in the direction of water flow, it is obvious that the condenser has the ability to exert a greater pull on the bottom stratum than it has on the top stratum in the zone P, the effectiveness of the pull increasing progressively in the direction of 100 water flow.

Since the water temperature gradually increases in passing over the successive trays, its air content progressively decreases, the air content being at a minimum adjacent the bottom 105 tray. The curve representing air removal is of the character ordinarily referred to as an asymptotic curve and illustrates the difficulty under natural conditions of operation of effecting complete air removal, the last quantity of air being removed only with considerably greater difficulty than the initial portions.

In accordance with applicant's invention, the upper steam stratum in the pressure zone wherein air may be removed comparatively easily has 110 a smaller steam flow than the bottom stratum, wherein air is removed with greater difficulty. The maximum steam flow from the stratum for the minimum air content insures the continuous 115 maintenance of an air-steam ratio in this stratum 120 such that the desired pressure equilibrium may be advantageously accomplished.

While I have herein illustrated and described strata of treatment of the type formed by superimposed trays, it will be understood that such 125 strata may be otherwise formed, and that the isolation or separation of the respective strata may be modified or changed in accordance with the particular design of the apparatus.

I claim:

1. A method of deaerating water including the steps of delivering the water to a chamber, supplying steam to the chamber to effect rapid heating and partial deaeration of the water, passing the partially heated water, the air released therefrom, and any uncondensed steam to a second chamber for further heat exchange, continuing the supply of steam through said first-mentioned chamber in an amount sufficient to maintain in the second chamber an atmosphere favorable to 130 further absorption of air from the water therein, withdrawing air and steam from the successive portions of the second chamber in amounts increasing progressively in the direction of water flow through said second chamber, and condensing any steam leaving the second chamber to create a pressure difference sufficient to maintain continued flow of steam through said chambers in the amounts aforesaid.

2. In a method of deaerating a liquid, the steps 135

including delivering the liquid to a chamber, supplying heated vapor to the chamber in sufficient quantities to effect rapid heating and partial deaeration of the liquid, passing the partially deaerated liquid, the air liberated therefrom and any uncondensed vapor to a second chamber, continuing the supply of vapor through the first chamber in quantities sufficient to effect further deaeration of the liquid in the second chamber, 10 removing the gaseous contents of successive por-

tions of the second chamber in amounts increasing progressively in the direction of the flow of liquid therethrough, and finally removing from the second chamber and condensing any previously uncondensed vapor therein, and controlling the quantity of vapor so finally condensed to maintain conditions in the second chamber favorable to continued deaeration. 80
